UNITED STATES PATENT OFFICE.

ANDERS A. SVENSEN, OF EVANSTON, ILLINOIS.

KEY-FASTENER.

No. 875,985.

Specification of Letters Patent.

Patented Jan. 7, 1908.

Application filed February 1, 1907. Serial No. 355,212.

Be it known that I, ANDERS A. SVENSEN, citizen of the United States, residing at 249 Evanston, in the county of Cook and State of Illinois, have invented a certain new and useful Improvement in Key-Fasteners, of which the following is a full, clear, concise, and exact description, reference being had to the accompanying drawings, forming a part of this specification.

My invention relates to locks and more particularly to key fasteners adapted to be associated with door locks or similar devices so as to prevent the manipulation of the key from the opposite side of the door.

My invention contemplates the construction of a device which is adapted to be disposed between the escutcheon plate and the door so that when keys are inserted into the lock, means are provided so that the key can be held securely within the lock and thereby prevent any manipulation or displacement of the key.

My invention will be more readily understood by reference to the accompanying drawing in which

Figure 1 illustrates an escutcheon plate to which my invention is applied; Fig. 2 is a rear view of Fig. 1; Fig. 3 is a sectional view taken on line 3—3 of Fig. 2; Fig. 4 shows a front elevation of my invention; Fig. 5 is a similar view showing a key in a locked position; Fig. 6 illustrates a modified form of my invention, and Fig. 7 illustrates an improved key for use in association with my device.

The device of my invention comprises a supporting plate 1 which is provided with lugs 2 and 3 provided with openings so that the plate can be secured to an escutcheon plate or to a door by means of rivets or screws 4 and 5. This supporting plate is provided at the upper and lower sides with portions 6 and 7 which are bent over so as to form guideways 8 and 9. The supporting plate has a keyhole 10 which registers with the keyhole in the lock. Secured to this plate is an additional member 11 which is also provided with a keyhole 12.

To form means for fastening a key after it has been inserted within the lock, there is mounted upon the supporting plate a movable plate 13 which is adapted to reciprocate in the guideways 8 and 9, this movable plate having a keyhole 14 which is normally in register with the keyholes 10 and 12. A spring 15 is secured to the supporting plate and has

one end engaging the movable plate and furnishes means for holding the movable plate in its normal position. After a key has been inserted within the lock, I provide means for actuating the movable plate so that the key can be fastened. To this end there is a lug 16 extending from the turned over portion 6, and a lever 17 pivoted at 18 has the eccentric portion 19 which is adapted to engage the movable plate when it is desired to bring it into locking engagement with the key, the lever 17 being provided with a thumb plate 20. The supporting plate 1 and the plate 11 are provided with teeth 21 and 22 respectively upon the circular faces of the keyholes 10 and 12. The movable plate is also provided with teeth 23. After a key has been inserted within the lock, the lever 17 is rotated about its pivot, thereby moving the plate 13 so that the teeth upon the supporting plate and movable plate will engage the key, as shown in Fig. 5, the key 24 as here shown being provided with teeth 25, thus providing the most suitable means for securely and rigidly holding the key in any desired position. To securely hold the movable plate into locking engagement with the key, the surface 26 of the eccentric portion 19 engages the edge of the movable plate, and as the lever is in its downward position, the plate will be prevented from actuation, and to further aid in holding the plate, the end 26 of the lever is brought into frictional engagement with the portion 7 of the supporting plate.

When it is desired to fasten keys which have flat shanks, the slot 27 formed at one side of the keyhole 14 is adapted for engagement with the key upon actuation of the movable plate. Fig. 6 shows a simplified construction whereby keys having flat shanks can be locked so as to prevent rotation. The movable plate 28, as here shown, is provided with an extension 29 terminating in a thumb plate 30. In order to insert a key within the lock, the plate 28 is moved to one side against the action of the spring 31, thereby bringing the keyholes into register. At one side of the keyhole 31 a slot 32 is formed which is adapted to engage the shank of a key to prevent displacement thereof. The stop 32 is formed upon the supporting plate so as to prevent greater movement of the plate 28 than is desired.

It will be apparent that the device which forms the subject of my invention is of a very simple construction and is easily se-

cured to any door or to the escutcheon plates of doors in such a manner that just a small portion will be visible,—namely, the actuating lever. It will be apparent to those skilled in the art that modifications can be made without departing from the spirit and scope of my invention. I do not wish, therefore, to be limited to the exact construction herein shown, but

19 I desire to secure by Letters Patent:

1. In a locking device for association with the lock of a door, the combination with a supporting plate adapted to be secured with respect to the lock, said plate having a key-hole in register with the lock keyhole, a movable plate mounted on the supporting plate and also having a keyhole, spring means tending to hold the movable plate and the key-hole therein in registration with the keyhole in the supporting plate, a lever pivoted to the supporting plate and adapted for engagement with the movable plate, teeth formed upon the supporting and movable plates, said teeth being adapted for engagement with the key after the actuation of the lever.
2. In a locking device for association with the lock of a door, the combination with a supporting plate adapted to be secured with respect to the lock, said plate having a key-hole in register with the lock keyhole, a movable plate mounted on the supporting plate and also having a keyhole, spring means tending to hold the movable plate and the keyhole therein in registration with the key-hole in the supporting plate, a lever pivoted

to the supporting plate, said lever having an eccentric portion for engaging the movable plate so that when said lever is actuated, the movable plate will be brought into engagement with an inserted key.

3. In a locking device for association with the lock of a door or the like, the combination with a plate adapted to be secured with respect to the lock, said plate having a key-hole in register with the lock keyhole, a movable plate mounted on the supporting plate and also having a keyhole, spring means tending to hold the movable plate and key-hole therein in register with the keyhole of the supporting plate, said keyholes having 45 teeth about their circular faces, said teeth being adapted for engagement with the shank of a key, a lever pivoted to the supporting plate, said lever having an eccentric portion adapted for engagement with the edge of the movable plate, said teeth being brought into engagement with an inserted key after the actuation of said lever the end 50 of the lever during actuation being brought into frictional engagement with the 55 supporting plate to assist in holding said lever in its locking position.

In witness whereof, I hereunto subscribe my name this 29th day of January A. D., 1907.

ANDES A. SVENSEN.
